DESIGN FOR A DOUBLE VANITY HANDBAG

Roland R. Lewenthal, New York, N. Y.

Application September 26, 1940, Serial No. 95,413

Term of patent 3½ years

To all whom it may concern:

Be it known that I, Roland R. Lewenthal, a citizen of the United States of America, residing in New York city, county of New York, and State of New York, have invented a new, original, and ornamental Design for a Double Vanity Handbag, of which the following is a specification, reference being had to the accompanying drawing, forming part thereof, wherein,

Figure 1 is a front view of a double vanity handbag showing my new design in a closed position.

Figure 2 is an end elevational view thereof.

Figure 3 is a front view showing the top flap open.

Figure 4 is a view showing the face turned upward to show the second compartment.

The opposite side of the handbag is substantially like the side shown in Figure 1, except that the upper flap is omitted.

The drawing is lined in several views to represent a contrasting colored appearance.

I claim:

The ornamental design for a double vanity handbag, substantially as shown and described.

ROLAND R. LEWENTHAL.
